UNITED STATES PATENT OFFICE.

WILLIAM B. SHEARER, OF MONTCLAIR, NEW JERSEY, ASSIGNOR TO INTERNATIONAL TORPEDO BOAT CORPORATION, OF WILMINGTON, DELAWARE, A CORPORATION OF DELAWARE.

TORPEDO-BOAT.

1,356,791.

Specification of Letters Patent. Patented Oct. 26, 1920.

Application filed December 10, 1917. Serial No. 206,407.

To all whom it may concern:

Be it known that I, WILLIAM B. SHEARER, a citizen of the United States, residing at Montclair, county of Essex, and State of New Jersey, have invented certain new and useful Improvements in Torpedo-Boats, fully described and represented in the following specification and the accompanying drawings, forming a part of the same.

10 This invention relates to certain improvements in floating dirigible explosive carriers, and the invention relates particularly to a boat where the explosive charge is a torpedo which is to be sent from the boat to its target.

15 The carrier is in the form of a boat having a compartment for the torpedo, a compartment for the engine for driving the boat, and a compartment for the operator, 20 the boat being constructed with a separable bow portion which can be elevated out of the way to permit the torpedo to be discharged from the compartment in which it is carried, the operation of moving the bow and firing the torpedo being under control of the operator.

25 The present invention has for one of its objects a construction by which the torpedo or other movable explosive charge may be loaded into the boat without water having access to the torpedo compartment, so that the torpedo can be loaded into the boat while the boat is in the water.

30 It is a further object of the invention to provide such a construction by which the tube now used for carrying the torpedo is eliminated and the torpedo may be loaded into its compartment without the necessity of pushing it into or through such tube.

35 It is a further and important object of the invention to provide a construction whereby the torpedo compartment may be flooded with water when it is desired to fire the torpedo, so that the torpedo may 40 be expelled from the compartment under its own power, the compartment being dimensioned to hold sufficient water to permit this to be done.

45 It is a further object of the invention to 50 provide improved devices for controlling the firing of the torpedo so that the torpedo can not be fired until the movable bow portion of the boat has been moved out of the

way and the torpedo compartment flooded with water, whereby any danger of premature firing of the torpedo is eliminated.

55 It is a further object of the invention to provide an improved construction for the protection of the operator against small arm fire, and for preventing wash from entering 60 the operator's compartment when the boat is under way in a rough sea.

65 It is a further object of the invention to improve in various details the body construction whereby a strong, rigid structure is provided, and one which is stable and which will lie low in the water so as to provide as small visibility as possible.

70 With these and other objects not specifically referred to in view, the invention consists in certain novel parts and features of construction which will, to provide a better understanding of the invention, be fully described in connection with the accompanying drawings, in which—

75 Figure 1 is a general top plan view, partly broken away, of the improved torpedo carrier;

80 Fig. 2 is a general side view of the construction shown in Fig. 1;

85 Fig. 3 is a vertical longitudinal section on an enlarged scale, showing the various controls and the torpedo in place and the movable bow portion in open and closed position, the latter in full lines;

90 Fig. 4 is a horizontal sectional plan view of the construction shown in Fig. 3, the view being taken on line 4—4 of that figure and certain parts being broken away;

95 Fig. 5 is a detail sectional plan view of part of the control system, taken on line 5—5 of Fig. 3;

100 Fig. 6 is an enlarged cross sectional view taken on the line 6—6 of Figs. 3 and 4;

105 Fig. 7 is a vertical sectional view of part of the control system on an enlarged scale, the section being taken on the line 7—7 of Fig. 5;

110 Fig. 8 is an enlarged cross sectional view, taken on line 8—8 of Fig. 3;

115 Fig. 9 is a sectional plan view of a portion of the bow guide track, partially broken away, the view being on the line 9—9 of Fig. 8;

120 Fig. 10 is a detail sectional view of part of the bow manipulating mechanism the sec-

tion being taken on the line 10—10 of Fig. 8 and on an enlarged scale;

Fig. 11 is a detail view, partly in section and partly broken away, of the torpedo 5 firing control;

Fig. 12 is a broken plan view of the supports on which the torpedo rests, the view being taken on line 12—12 of Fig. 6;

Figs. 13 and 14 are detail views, showing 10 devices for connecting the torpedo firing controlling rods, and

Fig. 15 is a detailed sectional view showing 15 the means employed for manipulating the rear stop or buffer for the torpedo.

Before taking up a detailed description of 20 these drawings, it may be stated that while the boat may be used from a land or other permanent base, it is so dimensioned that it may be carried in numbers by a war vessel 25 or other mother ship and launched therefrom, and is also so balanced that it will float as close to the water level as practicable to afford low visibility; that is, practically awash except for the conning tower or top 30 of the operator's compartment.

While the dimensions of the boat may be 35 varied as desired, and may embody structural features of different characters, it will include a water tight compartment 1 in which is located the driving mechanism, which may be an ordinary 4-cylinder gasoline engine marked generally 2, this compartment also providing a place for the operator and for the controls hereinafter referred to. The boat will also include a compartment 3, closed at its rear end by a water 40 tight bulkhead 4 by which it is separated from the control compartment 1, and closed at its forward end by a bow section 5, which may be arranged to be swung open to admit water to the torpedo compartment 3 and to leave a clear path for the egress of the torpedo. This torpedo compartment 3 is of any suitable dimensions, but will be sufficiently 45 large to accommodate a torpedo 6, which may be of any suitable or usual type, and an amount of water sufficient for the torpedo to leave the compartment under its own power. While a torpedo of conventional 50 shape has been shown, it will be understood that the invention contemplates the discharge of any type of torpedo or movable explosive carrier which can be discharged from the boat under its own power. The 55 boat will also include air tanks 7, 8 arranged at each side thereof, the function of these tanks being to balance the boat, prevent its capsizing, and to maintain it at the desired level.

The amount of water sufficient for the 60 torpedo to leave the compartment under its own power depends to some extent on the dimensions and weight of the torpedo. In the embodiment of the invention illustrated 65 it will appear from Fig. 6 that there

is a considerable space all around the torpedo in addition to the spaces at its ends, all which spaces are flooded when the bow is opened. With the common torpedo tubes which fit fairly closely around the torpedo 70 only a comparatively small body of water can be admitted,—so small in fact that if the torpedo's engine were started therein without also propelling it by compressed air or an explosive charge behind it the propellers 75 would race without sufficient resistance from the water to secure a good launching. A considerable volume of water is necessary to furnish, so to speak, the necessary abutment against which the back pressure of the 80 propellers is exerted to launch the torpedo easily and without racing of its engine. The water should be in considerable volume around the sides of the torpedo as well as at its rear end and should be preferably 85 150% or more of the volume of the torpedo.

The water should also extend at least to and preferably above the top of the torpedo 90 so as to support it in its proper horizontal position and so that there is little or no serious tendency of the torpedo to dip its nose as it leaves the bow of the boat. The air in the torpedo is compressible to a variable extent. It is usually compressed to such an extent that the torpedo when idle will float at the surface of the water or approximately so. The flooding of the boat with water which entirely surrounds the torpedo will, therefore, practically support the torpedo 95 in such body of water and ease the pressure on its guides so that it will move freely under its propelling power. And since the deck of the boat is practically awash the lifting pressure of the water on 100 the torpedo will be practically the same when it emerges as when it is within the boat.

One of the important features of the present invention consists in a novel method of 110 discharging the torpedo or other movable explosive carrier, whereby the torpedo is discharged from the boat under its own power and beneath the water level, thus eliminating the use of the torpedo tube ordinarily 115 used for effecting torpedo discharge and the use of compressed air or an explosive for effecting the discharge, and a simple and convenient construction has been provided for effecting this and for 120 effecting the loading of the torpedo into its compartment without the necessity of pushing it into or through such tube, and also for loading the torpedo into the boat while 125 the boat is in the water.

It may here be stated that the boat may be built of any suitable material, but preferably, and as illustrated, the hull may be made of oak planking 9 and ribs of metal 10 to form a strong rigid structure. The 130

movable bow portion 5 may likewise be of any suitable material, but preferably is formed of sheet iron or steel to afford rigidity and prevent accident in case of collision, 5 this bow piece having bottom and sides 11 and being of the usual bow form, with a flat closed top 12 preferably made integral with the bottom and sides of the bow piece.

In accordance with the invention, means 10 are provided for loading the torpedo into the compartment 3 while the boat is in the water, and so that the torpedo does not have to be pushed through a tube, and means are provided whereby the torpedo 15 may be held in position and kept from any undue movement in the compartment and discharged therefrom under its own power when desired. While the specific embodiment of these means may be varied within 20 wide limits, a simple and convenient construction is that shown in which (referring particularly to Fig. 6) there is provided an upper deck 13 covering the compartment 3, which deck may be of wood having an 25 under facing of sheet iron or steel 14. This upper deck, as shown in Figs. 1 and 3, extends substantially the length of the compartment 3 from the bulkhead 4 to the rear of the movable bow 5. This deck is arranged 30 to be movable, so that it can be swung out of the way to permit a torpedo to be lowered into the compartment 3, and, as shown, is hinged to the main hull by suitable hinges 15, one member of the hinge 35 being secured to the deck and the other to a sheathing 16, which is provided for covering the air tanks 7, 8, before referred to, and which has a portion extending inwardly over the sides of the boat, as shown 40 in Fig. 6. The deck, when closed, is prevented from swinging down into the compartment and is supported by stop shoulders 17 formed in brackets 18 suitably secured, as by bolts 19, to the hull of the boat.

45 Means are provided by the present invention for holding the torpedo in position in the compartment without substantial movement thereof and for guiding it and assisting its movement when it is discharged 50 therefrom under its own power, as herein-after explained. These guiding and positioning means comprise, in the particular construction illustrated, a metal frame 20 having side bars 21, 22 and cross bars 23.

55 This metal frame 20 is hinged at 24 to brackets 25 suitably secured, as by bolts 26, to the hull of the boat, this frame being hinged so that it may be lifted to permit the insertion of the torpedo into the compartment 3. The frame is prevented from falling 60 into the compartment and is supported by a stop flange 27 formed on the lower part of the bracket 18, before referred to, the frame resting on this flange when in 65 lowered position. The frame 20 is, as will

be observed, spaced from the deck 13 so as to prevent injury to the torpedo from the collapse of the deck 13 due to walking thereon or from other reason.

Carried by this frame is a guide which operates with a guide carried by the torpedo for guiding the torpedo as it leaves the chamber. While the specific construction of this guide may be somewhat varied, as illustrated it comprises a bar 28 to which 70 are secured spaced rails 29 having angular extensions or flanges 30, the flanges being disposed toward each other, as shown in Fig. 6, the bar 28 and the rails 29 being secured to the cross pieces 23 of the frame 75 by suitable bolts 31. Coöperating with these flanged guide rails is a guide carried by the torpedo which, as clearly shown in Fig. 6, is a T-shaped projection 32, this T-projection fitting loosely in the track 80 formed by the rails 29, 30, the rails and the T-projection acting to guide the torpedo 85 as the same moves from the compartment 3.

To facilitate the movement of the torpedo 90 from the compartment and to keep it free of the bottom, antifriction devices of any suitable character are preferably employed, these antifriction devices also acting as a support for the torpedo while in the compartment. The specific construction of these 95 devices may be somewhat varied, but in the particular construction illustrated, referring to Figs. 6 and 12, there are provided a series of two-part supports 33, 34 projecting angularly from the bottom of the boat on each 100 side thereof toward each other, these supports having mounted therebetween freely rotatable antifriction rolls 35, on which the torpedo rests, a sufficient number of these supports being provided to firmly support 105 the torpedo.

In constructions embodying the invention in its preferred form, the guide track, in which works the T-projection before referred to, will be extended beyond the compartment into the movable bow-part of the boat, so as to guide the torpedo after it has emerged from the compartment. While various constructions may be employed for effecting this, as shown (see Figs. 4, 9 and 10) there is provided a frame comprising cross pieces 36 bolted to angle irons 37 securely fastened to the hull portion of the boat. These frames 36 are bent at right angles to form forwardly extending portions 38 which are formed with flanges 39 (see Fig. 8) disposed toward each other to form a track. Side frames 40 are provided for bracing the parts 38, and the frames are furthermore braced by a top plate or bar 41 secured to the extension 38 of the frame 36. These frames extend, as shown in Fig. 4, forwardly into the bow of the boat and remain in fixed position, the bow of the boat and the hinged deck 13 and frame 20 125 130

being lifted away from them when the deck and frame are opened to give access to the torpedo compartment.

The torpedo is restrained from substantial movement in either direction in the compartment through devices which may be of various characters. Forward movement of the torpedo is restrained, where the torpedo is provided with a projection, by means of a stop 42 (Fig. 11) carried on one arm of a lever 43 pivoted at 44 in a block 44' secured to the rails 29, before referred to, on their inner ends, the other end 45 of this lever taking into a notch 46 formed in a rod 47 mounted so as to be movable on the frame 20 before referred to, the function of which rod is more fully described hereinafter. This stop 42 is normally in the path of the T-shaped projection 32 of the torpedo, and acts to hold the torpedo against substantial forward movement in the compartment.

Means are provided for preventing rearward movement of the torpedo to any substantial extent in the compartment, which means may be of various characters. In the particular construction illustrated, there is provided (see Figs. 3, 7 and 15) a buffer which is provided with a buffer-head 48 against which the tail of the torpedo may seat. The construction of this buffer, where such means is employed to prevent rearward movement of the torpedo, may be varied, but preferably will be such that it may be swung out of the way when the torpedo is being positioned in the compartment. In the particular construction illustrated, there is provided a flange 49 secured to the bulkhead 4, before referred to, which flange has secured thereto a head 50 having an extension 51. The extension 51 is pinned by a pin 52 to a block 53, so that the block 53 may be swung around the pin 52 as a pivot. The block 53 lies within a hollow cylindrical extension 54 extending from the buffer-head 48 and is pinned thereto by a pin 55 which works in slots 56 in the sleeve. By pulling the buffer to the left in Fig. 7, until the end of the sleeve passes the pin 52, the buffer may readily swing to the position shown in Fig. 15 and be out of the way of the torpedo when it is placed in the compartment. In loading the torpedo into the compartment, the deck and frame are raised and the torpedo placed in the compartment. The frame 20 is then lowered and the torpedo then given a slight forward movement to cause the projection 32 to engage the tracks 39, this movement bringing the projection on the torpedo against the stop 42. The buffer is then swung into place, and the buffer and stop are so dimensioned and positioned that any substantial forward or backward movement of the torpedo is prevented.

Means are provided, according to the pres-

ent invention, for lifting or opening the bow of the boat to flood the compartment with water, so that the torpedo can be discharged under its own power, for releasing the lock so that the torpedo may be fired, and for starting the driving mechanism of the torpedo so that it will leave the compartment and these means are preferably so interrelated that the torpedo-operating mechanism can not be put into action until after the bow of the boat is fully opened and the compartment flooded. While the various specific embodiments for effecting these objects may be varied, a simple and efficient one is that shown in which (referring particularly to Fig. 3) there is provided a rod 57 slidably supported in brackets 58 positioned on the hinged deck 13 before referred to. This rod is operated by a screw 59 engaging a nut 59' and an operating wheel 60 from the cockpit 1, before referred to, and this rod will hereinafter be termed the bow operating rod. This rod, by the turning of the wheel 60, is moved to open or close the bow 5 of the boat through any suitable connections, as by means of a short rod 61 secured to the rod 57, so as to move therewith, as by being pinned to a bracket 62 fast on the rod. The other end of this rod is pivotally secured to a bracket 63 mounted on the upper portion 12 of the bow 11 before referred to. By the movement of the rod to the right, as shown in Fig. 1, the bow of the boat is swung to the position shown in dotted lines in Fig. 3, the bow swinging on connections herein- after more specifically referred to.

Below the deck 13, and slidably supported in brackets 64 depending from the deck, is the rod 47 before referred to. This rod, at one end, is connected to and is operated by 105 a hand lever 65, this lever being controlled by a toothed sector 66. The rod 47 has two functions. The initial movement of the rod to the right causes the lever arms 45 to be swung to the right in Fig. 11, this swinging 110 movement of the lever operating to lift the stop 42 out of the path of the projection 32 on the torpedo. The further movement of the rod causes a trip pin 67 carried thereby to contact with and operate a firing pin 68 115 on the torpedo, this action throwing into operation the power mechanism of the torpedo and causing it to leave the compartment under its own power.

In order that the firing rod may not be 120 operated through the hand lever 65 until the bow has been fully opened, connections are provided between the bow rod and the firing rod so that the firing rod can not be operated until the bow rod has been moved a distance 125 sufficient to fully open the bow and free the compartment 3. While these connections may be of various characters, in the particular construction illustrated the firing rod is provided with a toothed ratchet 69 with 130

which coöperates a pawl 70 carried on the bow rod, the parts being so arranged that the firing rod can not be operated until the bow rod has been moved sufficiently for the 5 pawl to clear the ratchet. In this way there will be no danger of firing the torpedo until its path from the compartment is free and unobstructed, which is a very important feature of the device.

10 Both the bow rod and the firing rod enter the compartment or cockpit 1, the bow rod through the top of the compartment above the deck, and the firing rod through the water-tight bulkhead 4 below the deck. In 15 the best constructions, to prevent leakage into the water-tight compartment, stuffing boxes 71, 72 are provided for the bow rod and firing rod, respectively, these stuffing boxes being of any suitable character.

20 As the bow rod is carried by the hinged deck 13, and the firing rod by the swinging frame 20, and as these rods extend beyond the deck and frame, respectively, into the cockpit or compartment 1, means must be 25 provided whereby the decks can be swung on their hinges, carrying these rods with them. While the specific means employed may be somewhat varied, in the particular construction shown in Figs. 13 and 14, these 30 rods are two-part rods, and one end of one part of the rod is provided with a tongue 73 which fits between a pair of ears 74, a pin 75 being passed through the tongue and ears for holding them together, this pin 75 being 35 prevented from displacement by the usual cotter pin 76, this construction being adopted for both the rods.

With the construction shown and described for opening the bow, when the deck 40 and frame are to be opened to permit the loading of the torpedo into the torpedo compartment, it is necessary to uncouple from the rod 57 the short rod 61 which normally holds the bow in closed position, to permit 45 the opening movement. When this construction is employed, where a torpedo is being loaded into the compartment when the boat is in the water, it is preferable to provide some means for positively holding the 50 bow in position to prevent ingress of water into the compartment. While this may be provided in various ways, there is provided (Figs. 1 and 3) a supplemental clamping rod 77 pivotally secured to the bracket 63 55 secured on the bow portion, as before referred to, and arranged to be secured, as shown in dotted lines, to an eye 79 secured on the main deck of the boat at one side of the swinging deck 13, it being understood 60 that after the torpedo is in place and the deck is closed and the rod 61 is again coupled, this supplemental holding rod 77 is uncoupled from the eye 79 and swung to the position shown in full lines in Fig. 3.

65 The bow 5 is secured to the main hull, as

before stated, so that it can be swung away therefrom and leave a clear passage for the torpedo from the compartment 3, and in the best constructions connections between the movable bow and the remainder of the hull 70 are such as to stop ingress of water to the compartment when the bow is closed. While the specific construction for effecting this may be somewhat varied, as illustrated (see Figs. 3, 8 and 10) the bow is hinged to the 75 stationary top deck of the boat by hinges 80 on which it is swung up by the operating rod 61, before referred to.

The means for effecting a water-tight joint between the bow of the boat and the 80 hull may be of any suitable character. As illustrated, the forward end of the hull proper is cut out at its outer side, as indicated at 81 (see Fig. 9). The inner side of the end of the hull proper is recessed, as 85 indicated at 82, to receive a packing strip 83 held in the recess 82 by channel iron 82' and extending around the hull. Against this packing strip takes one leg of an angle iron 84 securely fastened on the inner end 90 of the bow portion. With this construction, when the bow portion is swung into place, it swings against this packing and affords a joint sufficiently tight to prevent substantial 95 ingress of water to the compartment.

In constructions embodying the invention in its best form, means will be provided for clearing the flooded torpedo compartment after the torpedo has been ejected, both when the boat is moving and when the boat 100 is standing still. While the specific construction for effecting this may be somewhat varied, it may include a bilge clearer marked generally 95, which is of any usual or suitable type, one of these clearers being 105 placed on each side of the boat and operating to siphon the water from the compartment after the operator has closed the bow while the boat is in motion. When the boat is standing still, the compartment may be 110 cleared by a pipe connection indicated generally by the numeral 96. This connection is controlled by a cock 97 so that connection is made between the pump of the motor and the compartment, and the motor acts to 115 draw the water from the compartment to and through the water-jacket of the engine.

The cockpit or operating compartment 1 is, as before stated, constructed so as to afford protection against small arm fire, and so as to be substantially water tight to prevent water from obtaining entrance therein. In the particular construction illustrated, the compartment above the water line is formed of sheet steel, the forward and rearward 120 sides of which are slanted, as shown at 85 and 86 in Fig. 3, through which the operator can see to manipulate the boat. The front wall 85 is or may be hinged, as indicated at 88, so that it may be swung back to get at 130

the engine, if for any reason this is necessary, and the top 89 may be hinged as at 90.

The boat may be steered by the usual wheel 91 through any suitable rope and 5 pulley construction 92.

It will be seen from the foregoing that a simple but effective torpedo carrier has been devised, which can be operated by one man, the torpedo can be discharged under its own 10 power, and the torpedo can not be fired until its path is clear, which are two important features of the invention. Furthermore, a craft of low visibility and great stability is provided. It will be understood that the 15 invention, as to its important features, is not to be limited to the exact construction shown and described, as various constructions could be devised for effecting these objects without departing from the invention, 20 and it is understood that such changes in construction are within the invention described and the claims appended.

What is claimed is:

1. A torpedo boat divided by a transverse 25 partition into a closed space for carrying its operating mechanism and a torpedo-receiving space with a deck which can be opened to admit a torpedo without opening the space carrying the operating mechanism.

2. A torpedo boat having a rear closed 30 space for carrying its operating mechanism, the remaining forward space being just sufficient in length to accommodate a torpedo.

3. A torpedo boat having a rear closed 35 space for carrying its operating mechanism, the remaining forward space being just sufficient in length to accommodate a torpedo, and having a deck which can be opened to 40 give direct access to said forward space and permit the introduction of a torpedo.

4. A torpedo boat divided by a transverse 45 partition into a closed space for carrying its operating mechanism and a torpedo-receiving space with a deck which can be opened to admit a torpedo without opening the space carrying the operating mechanism, said torpedo-receiving space adapted to be flooded with sufficient water to support the 50 torpedo so that it may be propelled through such water under its own power.

5. A torpedo boat divided by a transverse 55 partition into a closed space for carrying its operating mechanism and a torpedo-receiving space with a deck which can be opened to admit a torpedo without opening the space carrying the operating mechanism, said torpedo-receiving space adapted to be flooded with sufficient water to support the 60 torpedo so that it may be propelled through such water under its own power, and means for clearing the flooded torpedo-receiving space of water after the torpedo has been launched.

6. A torpedo boat having a closed space

for carrying the mechanism and an operator and a compartment for a torpedo which is cut off from said space and is adapted to float substantially awash while the closed space extends above said compartment to 70 enable the operator to direct the boat.

7. A boat having sufficient closed space for carrying its operating mechanism and for securing the desired flotation level, and having a torpedo-receiving space inclosed 75 directly by the sides, bottom and deck of the vessel and cut off from said closed space.

8. A boat having sufficient closed space for carrying its operating mechanism and for securing the desired flotation level, and 80 having a torpedo-receiving space inclosed directly by the sides, bottom and deck of the vessel and cut off from said closed space, the torpedo receiving space being closed by a wall which can be opened to flood the space 85 and permit the torpedo to be propelled out of the boat by its own power.

9. A boat having sufficient closed space for carrying its operating mechanism and for securing the desired flotation level, and 90 having a torpedo-receiving space inclosed directly by the sides, bottom and deck of the vessel and cut off from said closed space, the deck over this space being movable to permit the torpedo to be lowered while maintaining a horizontal position into this space.

10. A boat having sufficient closed space for carrying its operating mechanism and for securing the desired flotation level, and having a torpedo-receiving space inclosed 100 directly by the sides, bottom and deck of the vessel, the deck over this space being movable to permit the torpedo to be lowered while maintaining a horizontal position into this space, and means for holding down and 105 guiding the torpedo in this space, said means being also movable to permit the lowering of the torpedo.

11. A boat, substantially the entire fore 110 part of which is a torpedo-receiving space large enough to carry so much water that the torpedo may be propelled through such water under its own power.

12. A boat having a rear closed space and a forward space inclosed directly by the 115 sides, bottom and deck adapted to receive a torpedo and to be flooded with water in which the torpedo can propel itself by its own power.

13. A boat having a rear closed space and a forward space inclosed directly by the 120 sides, bottom and deck adapted to receive a torpedo and to be flooded with water in which the torpedo can propel itself by its own power and a bow adapted to be moved 125 from the line of said forward space.

14. A boat having a rear closed space and a forward space inclosed directly by the 130 sides, bottom and deck adapted to receive a torpedo and a bow adapted to be moved

from the line of said forward space to flood the same and means for starting the propelling mechanism of the torpedo so that it will launch itself by its own power from said flooded space.

5 15. A boat having a hull the inside cross-section of part of which constitutes an undivided torpedo-receiving and launching space.

10 16. A boat having a rear closed space and a forward space inclosed directly by the sides, bottom and deck adapted to receive a torpedo and to be flooded with water in which the torpedo can propel itself by its own power and a bow hinged to the forward end of the deck and adapted to be swung up out of line with said torpedo.

15 17. A boat having a rear closed space and a forward space inclosed directly by the sides, bottom and deck adapted to receive a torpedo, said deck being movable to permit introduction of the torpedo into said forward space without passing through said rear space.

20 18. A boat having a space for carrying and launching a torpedo inclosed directly by the sides, bottom and top of the boat.

25 19. A boat having a space for carrying and launching a torpedo inclosed directly by the sides, bottom and top of the boat said top being movable to permit introduction of the torpedo.

30 20. A boat having a torpedo-carrying space inclosed directly by the sides, bottom and top of the boat said top being movable to permit introduction of the torpedo and the bow of the boat being also movable to permit launching of the torpedo.

21. A boat having a torpedo-carrying space inclosed directly by the sides, bottom 40 and top of the boat and closed at its forward end directly by the bow of the boat, the bow being movable to permit launching of the torpedo.

22. In a torpedo or similar boat, the combination of a bow piece normally closing the compartment, and movable to clear the same, a hinged deck covering the compartment and independent of the bow piece, a hinged frame below the deck piece, and guides carried by the frame for guiding the torpedo as it is discharged from the compartment.

23. In a torpedo or similar boat, the combination of a bow piece normally closing the compartment and movable to clear the same, 55 a hinged deck covering the compartment and independent of the bow piece, a hinged frame below the deck piece, and a track supported from the frame and coöperating with a projection on the torpedo for guiding the torpedo as it is discharged from the compartment.

24. In a torpedo or similar boat, the combination of a bow piece normally closing the compartment and movable to clear the same, 65 a hinged deck covering the compartment and independent of the bow piece, a hinged frame below the deck piece, a track supported from the frame and coöperating with a projection on the torpedo for guiding the 70 torpedo as it is discharged from the compartment, and antifriction supports on which the torpedo moves as it is discharged.

In testimony whereof, I have hereunto set my hand.

WILLIAM B. SHEARER
